UNITED STATES PATENT OFFICE.

HENRY H. LAWRENCE AND ORSON S. PHILBRICK, OF OAKLAND, CALIFORNIA; SAID PHILBRICK ASSIGNOR TO H. H. LAWRENCE, JR., OF SAME PLACE.

BILLIARD GAME.

SPECIFICATION forming part of Letters Patent No. 662,948, dated December 4, 1900.

Application filed January 29, 1900. Serial No. 3,230. (No model.)

To all whom it may concern:

Be it known that we, HENRY H. LAWRENCE, residing at No. 1255 Broadway, and ORSON S. PHILBRICK, residing at No. 1241 Broadway, 5 in the city of Oakland, county of Alameda, and State of California, citizens of the United States, have invented certain new and useful Improvements in Billiard Games; and we do hereby declare the following to be a full, 10 clear, and exact description of said invention, such as will enable others skilled in the art to which it most nearly appertains to make, use, and practice the same.

This invention relates to improvements in 15 games and toys, and more particularly to billiard games.

In the drawings, Figure 1 is an isometrical perspective view of a billiard-board constructed in accordance with this invention. 20 Fig. 2 is a longitudinal vertical section. Fig. 3 is an enlarged detail view of a corner of the board. Fig. 4 is a detail view of one of the retaining-hooks.

The objects which the invention has in 25 view are to provide a simple and inexpensive construction of a board which will serve the purposes of a game of billiards and to so construct the same that it may be rotated to various positions to suit the convenience of 30 the player. Further, to provide an inexpensive construction of a cushion for causing the pieces to rebound from the sides and to provide means whereby resiliency of the same may be increased.

35 It consists in providing the board A with the raised sides or rails B B. The rails B B are cut away at the corners to form a square shoulder or rest for the screw-nuts d d. The screw-nuts d d are threaded upon the hooks 40 D D, which extend through the perforations provided in the corners of the rails B B. The hooks D D are provided to receive the continuous wire C. The corners of the rails B B where cut away are protected by metal corner-pieces E of an ornate design, said corner-pieces comprising top plates which rest 45 upon the rails and from which depend wings lying against the rail sides. The pieces thus fit over the corners (to which they are 50 movably secured, as by screws) and protect and hide the projecting ends of the hook-

rods and their nuts, these nuts being accessible, however, for the purpose of adjusting the hooks by removing the corner-pieces.

The wire C is tightened by setting up the 55 screw-nuts d d, the effect of which is to draw the hooks D D outward, each in a different direction from the other, with the effect of tightening the wire. This produces of the wire a spring between each of the hooks D, 60 which will throw off and away from the rails B the game-pieces F when thrown against the wire in simulation of the action of the cushion of the ordinary billiard-table. Whenever it becomes necessary to tighten the wire, the 65 corner-pieces E are removed and each of the screw-nuts is set up, thereby producing an even tension on all of the reaches of the wire. When the tension of the wire is properly adjusted, the corner-pieces are replaced in position. 70 The board as completed has no projecting part which might strike upon to tear the clothing of the player when the board is rotated. The board rests upon a small stationary standard G, to which it is engaged by 75 means of the central pivot-rod I, that shown in the drawings being an ordinary bolt, the head of which engages a block J, rigidly secured to the board A. In some instances we provide between the surfaces of the block J 80 and the standard G an ordinary ball-bearing. In some instances small rollers are substituted for the balls. In the large majority of instances, however, the antifriction-bearings described are dispensed with and the surfaces of the block and standard are permitted 85 to rest one upon the other, the construction being so light that the friction engendered is of no material inconvenience.

The rules for playing the game are those 90 of the ordinary game of billiards.

The game is played by contestants sitting 95 at or about a table, and the board A is rotated to any position which the player may desire to regulate the direction of his shot without necessitating a change of his own position.

Having thus described this invention, what is claimed is—

1. In a game-table having raised corners, 100 a hook extending diagonally and inwardly from each corner in a horizontal plane, a sin-

gle continuous wire cushion passing through the hook end of each hook and engaged thereby, and means for drawing each hook outwardly, whereby the wire is stretched evenly; 5 substantially as described.

2. In a game-table having side rails, a hook extending through a corner of said rails, and supported by the same, said hook engaging a cushion, means upon the outside of said rails for engaging the hook and holding it in position, and a corner-piece fastened to the table, said corner-piece abutting and protecting the said projecting hook end and its securing member; substantially as described.

15 3. In a game-table having side rails, a hook extending through a corner of said rails and supported by the same, said hook engaging a cushion, means upon the outside of said rails for engaging the hook and holding it in position and also for drawing said hook outwardly to tighten the cushion, and a removable corner-piece fastened to the table and extending about the said projecting hook end

and its securing member, whereby said hook end is protected, while the corner-piece can 25 be removed to permit adjustment of the hook; substantially as described.

4. In a game-table having side rails provided with a corner cut away to form a square shoulder, a hook extending through said corner and supported by the same, said hook engaging a cushion, means upon the outside of said rails for engaging the hook and holding it in position, and a corner-piece removably secured to said table, said corner-piece comprising a top plate resting upon the rail ends and a wing-nut fastened to the rail sides, whereby said corner-piece covers and protects the projecting hook end; substantially as described.

In testimony whereof we have hereunto set 40 our hands this 18th day of January, 1900.

HENRY H. LAWRENCE.
ORSON S. PHILBRICK.
